UNITED STATES PATENT OFFICE

2,446,067

COMBINATION BEVEL

William Thomas, San Francisco, Calif.

Application September 2, 1943, Serial No. 500,962

1 Claim. (Cl. 33—102)

1

This invention relates to a combination bevel, protractor, center head, gauge, compass, square, and in fact a general purpose instrument with the result attained by interchanging of the relation of the parts, and for individual use thereof, in coaction, or combination.

I aim to provide an instrument of the present general character which is an improvement over that especially disclosed in my copending application Serial No. 465,341, filed November 12, 1942.

The more specific objects and advantages will become apparent from a consideration of the description following taken in connection with accompanying drawings illustrating an operative embodiment.

In said drawings:

Figure 1 is a view in side elevation of my improved structure adjusted to the form of a square and having a center head attached thereto;

Figure 2 is a side elevation showing the parts of the invention secured in position for use as a gauge;

Figure 3 is a sectional view taken on the line 3—3 of Figure 1;

Figure 4 is a cross section taken on the line 4—4 of Figure 1;

Figure 5 is an elevation showing the parts in adjusted position for use as a bevel;

Figure 6 is a detail section taken on the line 6—6 of Figure 1;

Figure 7 is a detail section taken on the line 7—7 of Figure 1;

Figure 8 is a view showing the blade detached and used in connection with a board and peep sight;

Figure 9 is a view in plan of said blade and peep sight;

Figure 10 is a section taken on the line 10—10 of Figure 8, with the board omitted; and

Figure 11 is an elevation showing the parts in adjustment for use as a square.

Referring specifically to the drawings wherein like reference characters designate like or similar parts, a stock is provided as at 10 comprising two plates 11 preferably separably connected together as by a pivot bolt at 12 passing through suitable openings, and which pivot bolt 12 at 13 may be pointed to enable it to occupy the depression made by a center punch mark or the equivalent. In addition, any suitable bolt may be passed through registering openings or holes 14 adjacent one corner of the plates 11. Such plates may or may not be provided, along their longitudinal edges and end edge or otherwise, with flanges as at 15.

2

Such plates 11 have central longitudinal slots 16 with an enlargement 17 adjacent the free end of the plate whereby levels 18 and 19 that function like those in my aforesaid pending application may be optionally disposed. Such levels have stems 20 adapted to slide in the engaged slots 16 and they have feet 21 passable through either of the slots or enlargements 17 and adapted to overlap the plates between them. Any desired clamping pressure may be applied to the plates to clamp the feet 21 between the plates, by the bolt which occupies the openings 14.

It will be noted that the plates 11 on their outer surfaces are suitably calibrated, and it is to be borne in mind that on such surfaces or on any other surfaces of the instrument or its components one may stamp, etch, or otherwise delineate suitable tables, equations concerning the pitch, degrees, rises, and hypotenuse, or any other desired data.

Pivottally mounted on the bolt 12 with one end disposed between the inner ends of the plates 11 is a blade or tongue generally designated 22, the same being adapted for disposition at any desired angle, such as for use as a square as in Figure 1, a bevel as in Figure 5, or a square as in Figure 11.

The adjustment of the blade 22 to these different positions is permissible since it has a slot generally of L shape consisting of communicating branches 23 and 24. However, the blade is adapted to swing when the bolt 12 is at the intersection of the branches 23 and 24, since its inner edge under such conditions is in line with the pivotal axis of the bolt 12 as in Figure 1. It will be noted that the blade 22 along its opposite longitudinal edges has suitable calibrations at 25 and 26 and that along its arcuate edge it is provided with protractor calibrations or indications 27. Viewing the blade as in Figure 1, the indications 25 and 26 being in inches, zero starts at the longitudinal median line of the stock 10 intersecting the center of the bolt 12. The blade 22 has a central longitudinal slot 28 extending inwardly from one end and also has an arcuate slot 29 concentric with the center 12 and protractor calibrations 27. Slot 28 will accommodate the use of either level 18 or 19, or any equivalent or other accessory therein.

In Figure 2 I have shown the parts described in position for use as a gauge. It will be noted that one end of the blade 22 extends below the stock 10 for gauging purposes, the lower edge of the stock 10 being adapted to rest on a board or piece of work being gauged. Also the blade 22

is adjustable longitudinally of the stock 10 for gauging purposes, in view of the elongation of the slot 23.

In Figure 4 I have shown a bolt at 11a occupying the openings 14. This bolt may be conventional or it may have a center punch 11b thereon for marking purposes; and also to enable it to occupy or enter a mark in connection with its work.

In Figure 5 the parts described are shown adjusted to a position where the structure forms a bevel. It will be noted that the blade 22 extends on one side of the stock or one of the plates 11, while the other plate is at an angle on the other side of the first-mentioned plate 11.

It will be noted from Figures 5 and 6 that the levels or other accessories such as 18 and 19, which here are designated 18a and 19a respectively, have a different or modified form of means whereby they may be mounted in the slots 16, 28, or the equivalent. To this end spaced spring fingers 30 extend from each and they have on their outer edges spaced-apart projections 31 and 32, providing notches 33 between them. Such fingers 30 are tensioned to spring apart slightly at their free ends, and as a result will frictionally remain in place. The plates 11, blade 22, or other parts are adapted to be engaged in the slot by the notches 33 with the projections 31 and 32 being disposed on opposite sides of them.

As best shown in Figures 1 and 6, I may use a center head in connection with the structure, the same being generally designated C. This center head may be used for various purposes, as in finding the centers of shafts, cylinders, and various other purposes. It consists of one bar 34 of L shape, preferably in one piece and rigid, and a pair of separate bars 35 conforming to the wings or angles thereof, not touching each other, as shown in Figure 6, to accommodate connection to parts where there is a flange. Said bars 34 and 35 are connected together by clamping bolts 36, and it will be noted that one of them passes through the opening or slot 28 to secure the center head to the blade 22.

In Figures 8, 9, and 10 the blade 22 is shown detached and as when used in connection with a board 37. In such use a peep sight of general construction 38 also may be used, the level line being indicated at 39. This peep sight has mounting fingers at 40 arranged to spring together at their inner ends and having lugs 41 thereon whereby they adjustably may engage the arcuate slot 29 or the elongated slot 28, as preferred for the particular use and according to the shape of the particular lug. It also will be seen in Figure 8 that the fingers 40 have elongated slots 42 to enable them to accommodate a bolt to fasten the center head C thereto or to accommodate the mountings or levels or other accessories such as those at 20 and 30.

In Figure 11 the structure is shown in the adjustment at which it is capable of use as a square. It particularly will be noted that this use is pos-

sible since the shorter slot or branch 24 at its closed end is in engagement with the pivot bolt 12.

The plate 11, blade 22, and bars 34 and 35 may be of metal, plastic, or otherwise and sufficiently pliable or flexible to adapt themselves on round or uneven surfaces.

It will be understood that I have discussed the use of the invention and its parts in only a general way and that such invention and parts are not to be restricted to the uses suggested, but are capable of broad and general application.

Various changes may be resorted to provided that they fall within the spirit and scope of the invention.

I claim as my invention:

A structure of the class described comprising a stock consisting of spaced plates, a blade, a bolt pivotally and slidably securing the blade to the stock for disposition of a portion of the blade between the plates of the stock, said blade having a substantially L-shaped slot engaged by the bolt and including a portion extending substantially longitudinally of the blade for adjustment of the blade longitudinally of the stock when said parts are disposed substantially parallel, said blade being of a length to extend adjustably beyond the free end of the stock to serve as a gauge with said free end engaging the work, said slot permitting pivotal adjustment of the blade to various angles and positions relatively to the stock to form a bevel or square and with said bolt disposed in various portions of the slot, and said slot having an arcuate enlargement at its apex in which said bolt is normally disposed when the parts are positioned to form a bevel or square.

WILLIAM THOMAS.
